UNITED STATES PATENT OFFICE.

WILLIAM J. ASHER, OF WILLIMANTIC, CONNECTICUT.

ROLL FOR PAPER-MACHINES AND OTHER PURPOSES.

No. 896,346.

Specification of Letters Patent.

Patented Aug. 18, 1908.

Application filed February 8, 1907. Serial No. 356,482.

To all whom it may concern:

Be it known that I, WILLIAM J. ASHER, a citizen of the United States, residing at Willimantic, in the county of Windham and 5 State of Connecticut, have invented certain new and useful Improvements in Rolls for Paper-Machines and other Purposes, of which the following is a specification.

My invention relates to rolls adapted to be 10 used in connection with paper making machinery and other purposes, and it has for its object to provide an improved roll having the general characteristics and capacities herein-after stated, and it consists in a roll embodying the various features of construction and arrangement of parts operating substantially as hereinafter set forth to accomplish the results in a manner substantially as described.

Referring to the accompanying drawings 20 wherein I have illustrated preferred embodiments of my invention sufficient to disclose the general character and principles thereof— Figure 1 is a transverse section of a roll showing one form and a covering therefor; Fig. 25 2 is a partial side view of a roll such as shown in Fig. 1, with the covering removed; Figs. 3 and 4 are respectively transverse sections of a roll showing different arrangements of the curved springs; and Figs. 5 and 6 are 30 respectively a transverse section and a partial side view of a roll showing a different form of curved springs and means for attaching them.

The general object of my invention is to 35 provide a roll which shall have a yielding or elastic surface to a greater or less degree, depending upon the particular purpose for which the roll is used. Such a roll of this general character, it is evident, can be used 40 for many and various purposes, and it can be variously constructed and arranged to adapt it for the particular purpose for which it is intended. It can be constructed to have varying degrees of elasticity, or to yield to a 45 greater or less extent under a given pressure.

It can be used by itself or be covered with any desired material or in any desired way to form a surface adapted for the purpose for which the roll is intended. It is evident 50 from these statements that while I have illustrated a preferred embodiment of my invention I have not limited it to the particular form of construction or arrangement of parts shown, as these can be varied by those

skilled in the art without departing from the 55 spirit of my invention.

Generally speaking, my improved roll comprises a series of curved springs, and these springs are mounted upon a suitable support in such a way that the curved springs 60 practically constitute a cylinder having more or less elasticity or flexibility and capable of yielding to a greater or less degree. The support for the curved springs may be in any suitable form adapted for the purpose, and 65 while I shall illustrate a preferred form, it is evident that other forms which are capable of accomplishing substantially the same result in substantially the same way may be used. So too, the curved springs may be of 70 different materials and of different shapes and lengths, and may be mounted and secured upon the support in different ways, so long as a roll of the general character herein described is made.

I will now more specifically describe the embodiment of my invention illustrated in the drawings, wherein

A is a support shown in this instance in the form of a metallic cylinder, supported at its 80 ends in any suitable way as by a head piece A' having a suitable hub A² adapted to be mounted on a suitable shaft A³, and this head may be provided with suitable openings A⁴, and the cylinder may have more or less openings A⁵. The number and arrangement of these openings of course will vary according 85 to the purposes for which the roll is used, and if the roll is used as a couch roll there may be numerous openings A⁵ in the cylinder, and 90 the opening or openings A⁴ in the head may be arranged to be connected with some conduit or suction means by which moisture may be drawn through the roll and discharged, or if, for instance, the roll is used for 95 drying purposes in connection with heated surfaces or otherwise, the openings in the cylinder and head will permit the discharge of steam from the roller.

Suitably mounted upon the support, and 100 in the present case upon the cylinder A, is a series of curved springs B. These springs may be of different material and shape, as above intimated, but as shown in Figs. 1 to 4, they consist of curved rods or wires cylindrical in cross section and secured at their ends to the cylinder A. Many and various ways of securing them may be used, but in

the embodiment referred to the rods B are bent at their ends, as at b, b', and are inserted in holes or openings a, a'. In the present instance there are rows of holes a, a' in the surface of the cylinder adjacent each other, and there may be any desired number of such rows, I having shown in the present instance four sets of rows at practically 90° apart. One end of each curved spring or rod is shown as being inserted in one of the holes or openings indicated by the letter a, and the other end of the curved spring or rod is shown as inserted in one of the holes of one of the series indicated by a'. These curved springs 10 may be of any desired length, and while preferably all the springs of a roll are of the same length, the roll may be made up of springs of varying lengths. In Fig. 1 the rod or spring indicated by letter B is made of a length 20 about once and a quarter the circumference of the cylinder. Thus the end b of the rod B is inserted in the hole a of one series and then the spring rod encircles the cylinder and extends to the hole a' of the next series, where 25 its bent end b' is secured thereto. It will be observed that the curved spring is not in contact with the surface of the cylinder, except at its extremities, but extends outward therefrom, leaving a greater or less space between 30 the surface of the cylinder and the circumferential plane of the curved spring. The next succeeding curved spring, in this instance indicated by C, has its end c secured to the opening a adjacent the opening a' receiving 35 the adjacent end of the spring B, and this spring C extends approximately once and a quarter around the cylinder, and its end c' is secured in an opening a' of the next series of openings from that to which its end first referred to is secured. In this way, it will be seen that the successive curved springs are secured so as to follow each other and constitute a cylinder made up of a practically continuous spiral, there being breaks in the continuous spiral at the points where the adjacent ends of two curved springs are secured. 45

In Fig. 3 I have shown another embodiment of the invention, wherein the curved springs D are longer than in the embodiment just described, and the end d is secured at one of the openings a of one set, and the end d' is secured at one of the openings a' of a set diametrically opposite the first, so that the rods or springs make practically one and 55 one-half circles around the surface of the cylinder.

In Fig. 4 I have indicated a construction wherein the springs E are shorter, and the end e is secured to an opening a of one set, 60 and the end e' is secured practically 135° from the first set, and thus the rods or springs make less than a complete circle around the surface of the cylinder. These illustrations are sufficient to indicate that the length of 65 the curved springs may vary, and they may

be variously arranged with relation to each other. In this Fig. 4 I have shown another way of securing the springs in which, specifically speaking, the spring may be of any desired length, and may make any desired number of turns around the cylinder, but may be secured thereto at intermediate points, so as to practically constitute a series of spiral springs. In this form I have shown what may be termed a headless screw S having a groove s into which the rod or spring is inserted, and secured in any suitable way as by heading over the adjacent parts of the screw. It will be seen that this accomplishes practically the same result in making an elastic 80 cylindrical surface, and securing it to the cylinder, although the spring may be continuous to a greater or less extent. 70

In Figs. 5 and 6 I have shown the spring sections F as having a flat outer surface, and 85 as preferably made of flat spring metal, and of a width so that when they are mounted spirally as indicated the sides of two adjacent portions of the spring or springs abut against each other throughout the greater 90 portion of their length. So too, I have for purposes of illustration of the scope of my invention indicated another means of securing the curved springs to the cylinder, and in this case there are rows of single holes a², a³, 95 and the bent ends f and f' of the spring F are inserted in the holes a², a³, and these holes also receive the ends of the next preceding and succeeding spring, as e' of the spring E and g of the spring G, and these ends may be 100 secured in the holes in any suitable way, as by a wedge W which can be readily driven in between the ends of two adjacent springs and secure them in position in their respective holes. 105

The roll thus far described may be used for any purpose for which it is adapted, or for other purposes it may be provided with any suitable cover adapted for the purpose for which it is intended, and as illustrative of this feature of the invention, in Fig. 1 I have shown a cover H made up of a series of layers of textile fabric, the inner one h being for instance of cotton, the next one h' being of wool, and the outer one h² being of canvas. 110 This cover can be attached and secured in a manner well understood in the art, and may be of any desired thickness. When the roll is used as a suction roll it may be suitably covered to adapt it for that purpose, as, for 115 instance, the covering may consist of a foraminous sheet of wire mesh or other well known material. 120

From the above disclosure of my invention the distinguishing characteristics thereof will 125 appear with sufficient clearness to enable those skilled in the art to make and use my invention, and to vary the details of construction and arrangement to adapt it for the purposes intended. 130

Without limiting myself to the particular construction described, and using the terms in the claims generically to include what is shown and the equivalents thereof, what I claim is:—

- 5 1. A roll of the character described, comprising a support and a series of springs arranged side-by-side and supported therefrom at both ends.
- 10 2. A roll of the character described, comprising a support and a series of curved springs having their ends connected to the support.
- 15 3. A roll of the character described, comprising a support, and a series of curved springs mounted on the support side-by-side close together and in series relation to form a cylinder.
- 20 4. A roll of the character described, comprising a support, and a series of curved springs mounted side-by-side and in spiral series relation close together to form a cylinder, each spring being supported at each of its ends.
- 25 5. A roll of the character described, comprising a cylinder, and a series of curved springs having their ends secured to the cylinder and arranged to form a yielding cylindrical surface.
- 30 6. A roll of the character described, comprising a cylinder, and a series of curved springs having their ends secured to the cylinder, the adjacent ends of two springs being secured together and to the cylinder.
7. A roll of the character described, comprising a support, and a series of curved springs, each extending a greater or less distance around the support and mounted side-by-side in a spiral series to form a cylindrical surface adapted to yield inwardly. 40
8. A roll of the character described, comprising a series of springs mounted to form a yielding cylinder, and a covering therefor.
9. A roll of the character described, comprising a series of springs mounted to form a yielding cylinder, and a covering of textile fabric. 45
10. A roll of the character described comprising a support and a series of similarly curved elastic rods secured thereto at their ends and arranged spirally and close together on the support so that said rods form a substantially continuous cylindrical spring surface. 50
11. A cylindrical roll the surface of which is composed of elastic rods extending around the cylinder and supported at intervals. 55
12. A cylindrical roll having a central support and a spring surface composed of spring rods wound spirally around said central support in close contact and supported therefrom at intervals. 60

In testimony whereof I affix my signature in presence of two witnesses.

WILLIAM J. ASHER.
